UNITED STATES PATENT OFFICE.

ANDREW CAMPBELL, OF BROOKLYN, ASSIGNOR TO JOHN AND EDMUND McLOUGHLIN, OF NEW YORK, N. Y.

MECHANISM FOR SHIFTING THE ANGLE-ROLLERS OF PRINTING-PRESSES.

SPECIFICATION forming part of Letters Patent No. 284,607, dated September 11, 1883.

Application filed March 5, 1883. (No model.)

To all whom it may concern.

Be it known that I, ANDREW CAMPBELL, a citizen of the United States, residing at Brooklyn, Kings county, New York, have invented 5 certain Improvements in Mechanism for Shifting the Angle-Rollers of Printing-Presses, of which the following is a specification.

In mounting the inking-rollers of a printing-press certain of these rollers are mounted 10 to extend obliquely across the line of movement of the reciprocating part to which the ink is to be applied, or on which the ink is to be distributed. When fixedly mounted at pre-determined angles, the rollers do not distribute 15 perfectly, as they always present the same points on their surfaces to the same points on the reciprocating surface.

My invention seeks to correct these defects in the distribution by shifting the roller so as 20 to change its angle a little at each movement of the reciprocating part, so that it may not present itself at the same angle to the said part twice in a great number of reciprocatory movements of the latter. In fact, I make the 25 movements of the parts incommensurate, so that it may require an almost infinite number of reciprocations to bring the parts back to their same relative positions as at starting—that is to say, it is possible to so construct 30 the mechanism that the angle-roller will not present itself twice at the same angle to the same point on the reciprocating part in a million revolutions of the printing-cylinder. Thus I am enabled to effect a near approach to perfection in the distribution of the ink.

The mechanism I prefer to employ in carrying out my invention is illustrated in the accompanying drawings, wherein—

Figure 1 is a mutilated side elevation of a 40 part of a printing-press, showing the construction and arrangement of the mechanism for shifting the rollers. Fig. 2 is a sectional end elevation of the same, taken on line 2 2 in Fig. 1. Fig. 3 is a plan, and Fig. 4 is a 45 modification, that will be referred to herein-after.

Let A represent a part of the side frame of a printing-press of any kind, and B a rabbet-strip or angle-strip mounted on and secured to 50 said frame. In the angle of the strip B is mounted a slide, C, which is retained in place,

but permitted to slide a limited distance longitudinally, by means of bolts *a*, which play in slots in B. In the slide C are mounted the forked swivel-bearings *b b* for the angle-rollers 55 D. The other ends of these rollers are similarly mounted; but the forked bearings at that end need not be mounted in a slide.

In order to shift the angle of the rollers, I employ the mechanism which I will now describe. 60

Pendent from the slide C is an arm, *c*, which is coupled to a connecting-rod, *d*. On the end of this rod is a strap which embraces an eccentric, *e*, on a shaft, *f*, mounted in the press-frame. Mounted also on the said shaft *f* is a disk or wheel, *g*. The shaft *f* may be made 65 rotative, and the eccentric *e* and disk *g* be fixed thereon; or the shaft may be fixed, and the eccentric and disk be mounted loosely 70 thereon. In this case, however, the eccentric and disk must be secured together.

Mounted loosely on shaft *f* is an arm, *h*, which bears a pawl or dog, *i*, arranged to bite 75 into the periphery of the disk *g* when the arm is moved forward, and to slip over its surface when the arm is moved backward. The arm *h* may be caused to reciprocate in any way; but I prefer to couple its pendent end to a connecting-rod, *j*, and to couple the other end of 80 said rod to a crank, *k*, on a shaft, *l*. This shaft may be mounted in the press-frame and be driven from the same mechanism that reciprocates the bed of the press. When the crank *k* rotates, the arm *h* is swung back and forth 85 on shaft *f*. This causes pawl *i* to bite on disk *g* and rotate it intermittently. The eccentric *e* will also be rotated intermittently, and the slide C be thus caused to move by steps or intervals in one direction a distance equal to the 90 throw of the eccentric, and back again by steps.

Now, if the crank *k* be arranged to turn once at each reciprocation of the press-bed, it will be seen that each intermittent movement of the rollers will correspond with 95 a reciprocation of the bed, and thus the angle of the rollers will be changed at each of said reciprocatory movements of the bed. Now, if it requires, say, twenty revolutions of crank *k* to produce one revolution of the disk *g*, then 100 the rollers will be capable of assuming ten different angles with respect to the axis of the

movement of the bed; but in order to vary these angles to an almost infinite extent I make the circumference of the disk *g* incomensurable with the throw of the pawl *i*—that is to say, the circumference of the disk is not divisible by the annular intermittent impulse imparted by the pawl without a remainder. Thus the rollers will not present themselves twice at the same angle to the same part of the reciprocating bed, except at long intervals. The revolutions of the crank *k* might also be made non-synchronous with the movements of the reciprocating bed, and also incomensurable therewith—that is to say, the crank may not make its revolutions at the same time with the reciprocation of the bed, nor in the same period.

The mechanism may be so arranged that the rollers will shift their angles while the bed is passing under them, or the shifting may be done while the rollers are unemployed.

In lieu of a crank, *k*, arranged to give a regular oscillating movement to the pawl or dog *i*, I may employ a cam to move said pawl forward, and a spring, *m*, to retract it, as shown in Fig. 4; or any other well-known mechanical means may be employed for actuating said pawl.

In lieu of a smooth disk, *g*, I may employ a ratchet-wheel with fine teeth, and in lieu of the lifting dog or pawl *i*, I may employ a friction-brake shoe of a well-known construction.

In order to prevent the disk from being rotated backward, I employ a gravity dog or pawl, *n*, mounted as shown in Fig. 1.

The rollers may be mounted in such a manner as to always stand at some angle, more or less acute, with the axis of the movement of the bed. This is shown in Fig. 3, where the full lines show the rollers at their most acute angle with the axis of the bed, and the dotted lines show the most obtuse angle. The rollers may, however, be arranged to stand at one point at right angles to the bed-axis, and to shift to both sides of this line. This is a matter of skill and judgment on the part of the constructor.

E, in Figs. 2 and 3, represents the reciprocating bed of the press.

I may also arrange the rollers to be shifted at both ends by employing two sets of shifting mechanism; but I do not find any advantage

in this; and I may also employ a crank in lieu of the eccentric *e*.

Having thus described my invention, I claim—

1. In a printing-press, means, substantially as described, for intermittently shifting and varying the angles of the angle-rollers, where in the movement of the shifting mechanism is made incomensurable with the movements of the reciprocating bed, and whereby the rollers are presented to the bed at constantly-varying angles, in order to effect a better distribution of the ink, substantially as set forth. 65

2. As a means for shifting the angle of the angle-rollers of a printing-press, a slide mounted on the press-frame to receive the swiveled bearings of the rollers, the said bearings and mechanism, substantially as described, for imparting an intermittent step-by-step motion to said slide, substantially as set forth. 70

3. As a means for shifting the angle of the angle-rollers of a printing-press, a slide mounted on the press-frame to receive the swiveled bearings for the rollers, the said bearings, a connecting-rod, and eccentric arranged to impart to said slide a reciprocating motion, a disk, *g*, arranged to rotate with the eccentric, and means, substantially as described, for imparting an intermittent rotating motion to said disk *g*, substantially as set forth. 75

4. As a means for shifting the angles of angle-rollers for printing-presses, a slide mounted on the press-frame and provided with bearings for one end of the roller, a connecting-rod and eccentric arranged to impart a reciprocatory motion to the said slide, a disk, *g*, mounted to rotate with said eccentric, and a radially-mounted pawl, *i*, or its specified equivalent, provided with means for imparting to said pawl a swinging reciprocating motion, whereby the disk will be intermittently rotated, the distance through which said pawl moves being incomensurable with the measure of the circumference of the disk *g*, substantially as and for the purposes set forth. 80 90 95

In witness whereof I have hereunto signed my name in the presence of two subscribing witnesses.

ANDREW CAMPBELL.
